Attorneys

UNITED STATES PATENT OFFICE.

LEONARD D. GOFF, OF THREE RIVERS, MICHIGAN.

BOILER-FEED DEVICE.

Application filed July 16, 1925. Serial No. 44,019.

This invention relates to improvements in boiler feed devices.

The main object of this invention is to provide an improved apparatus whereby the 5 condensate or return water is effectively delivered to the boiler.

A further object is to provide an apparatus having these advantages which is not likely to become inoperative or "hung up" 10 in use.

A still further object is to provide an improved apparatus of the class described which is very simple and economical in structure.

15 Objects relating to details and economies of construction and operation will definitely appear from the detailed description to follow.

I accomplish the objects of my invention 20 by the devices and means described in the following specification. The invention is clearly defined and pointed out in the claims.

A structure which is a preferred embodiment of my invention is clearly illustrated 25 in the accompanying drawing, forming a part of this application, in which:

Fig. I is a diagrammatic view of an apparatus embodying the features of my invention, the parts being shown mainly in 30 conventional form.

Fig. II is a detail view partially in vertical section on a line corresponding to line 2-2 of Figs. I and III.

Fig. III is a detail view mainly in vertical section on a line corresponding to line 3-3 of Fig. II.

In the drawing similar reference characters refer to similar parts throughout the several views, and the sectional views are 40 taken looking in the direction of the little arrows at the ends of the section lines.

Referring to the drawing, I have shown 45 my improvements as embodied in a heating system in which 1 represents the boiler, 2 the distributing pipe and 3 the return pipe. These parts are shown conventionally.

The trap casing 4 is connected to the return pipe, the return pipe having the **T** coupling 5 therein connected to the bottom 50 of the trap casing. At each side of this trap connection the return pipe is provided with a check valve 6.

The trap casing has a relief port 7 controlled by the outwardly seating valve 8, the 55 relief port being connected by the pipe 9

to deliver into the ash pit of the boiler. It may, however, be vented to atmosphere or into a lower pressure.

The trap casing also has an inlet or pressure port 10 controlled by the inwardly seating valve 11, the port being connected to the boiler through the pipe 12. These valves are operatively connected so that the pressure valve 11 is opened when the valve 8 is closed and vice versa. Thus arranged, the pressure acts to hold both the vent and pressure valves to their seats.

The valve operating means consists of the lever 13 which is pivoted at 14 on the hangers 15 depending from the top of the casing, the lever having a cross arm 16 through which the stems 18 and 19 of the valves are arranged, spherical stops 20 being arranged on the stems at each side of the arm. This provides a loose connection which allows 75 for a slight lost motion preventing the cramping of the parts and permitting the complete seating of the valves.

The float rod 21 is arranged through the lever and has spherical stops 22 thereon 80 at each side of the lever. The float 23 is slidable on the rod 21, the rod being provided with tappets 24 and 25 with which the float alternately engages as the water rises and falls in the float chamber.

To prevent the collapsing of the float under pressure and also to permit equalizing of pressures within the float thereby affecting its buoyancy and to exhaust water of condensation from slight leakage, I provide 85 a vent pipe 26 which opens to the outside of the float at the top thereof or above the line of buoyancy and into the float at a point adjacent its bottom.

With the parts thus arranged, the operation of the float is as follows:

In the initial starting of the apparatus the float would of course be at its lower position, the valve 11 being closed and the valve 8 open, as shown in Fig. III. The pressure of the water on the valve 6 at the boiler side or left hand side of the float holds this valve on its seat so that return water will flow into the trap casing, lifting the float until the buoyancy thereof is sufficient to open the valve 11 and close the valve 8. This admits boiler pressure to the trap casing and closes the right hand check valve 6, allowing the water to flow into the left hand check valve. The float being 100 105 110

vented, pressure within the float corresponds to the variation of pressure in the float or trap casing so that the float is not collapsed, and further, any water condensation or leakage is drawn off when the pressure is released as occurs when the valve 11 is again closed and the valve 8 opened. Both the relief and pressure valves open against pressure so that as the float rises it engages the tappet 4, but the pressure valve is not opened until the buoyancy of the float is such as to overcome the pressure in the pipe 12 tending to hold the valve 11 to its seat, the result being that as soon as the buoyancy has reached the desired point to lift the valve 11 from its seat, a quick or "snap" action takes place, opening the valve 11 fully. A reverse of this action occurs as the float rides down on the discharging water, the pressure tending to hold the valve 8 to its seat until the weight of the float overcomes this action and sufficient water will have been discharged to allow substantial fall of the float at this time quickly closing the pressure valve.

I have illustrated and described my improvements in a very simple and practical embodiment. I have not attempted to illustrate and describe various modifications and adaptations which I contemplate as I believe the disclosure made will enable those skilled in the art to embody or adapt my improvements as may be desired.

Having thus described my invention, what I claim as new and desire to secure by Letters Patent is:

1. In an apparatus of the class described, the combination of a return pipe provided with a pair of check valves, a trap casing connected at its lower end to said return pipe between said check valves, a pressure connection to the top of said trap casing, an inwardly seating valve for said pressure connection, an outwardly seating relief valve at the top of said casing, a pivoted lever, said pressure and relief valves having a direct pivotal connection to said lever whereby they are alternately opened and closed as the lever is actuated, a float rod having a direct pivotal connection to said lever and provided with spaced tappets, a closed float slidably mounted on said rod to coact with said tappets whereby the relief valve is closed and the pressure valve opened when the float is lifted and the pressure valve is closed and the relief valve opened when the float falls, said float, being of such proportion that the buoyancy thereof when submerged beyond its floating point is sufficient to overcome the resistance of the pressure on the pressure valve will actuate the lever with a snap action to open said valve without the aid of a spring, and of such weight that when the resistance of the pressure on the relief valve is overcome by

the falling of the float the lever will be actuated with a snap action to open said relief valve without the aid of a spring, and a vent pipe for said float opening at the top thereof and opening into the float at a point adjacent the bottom thereof whereby the interior of the float is subject to the variations in pressure within the casing and water is exhausted from the float. 70

2. In an apparatus of the class described, 75
the combination of a return pipe provided
with a pair of check valves, a trap casing
connected at its lower end to said return
pipe between said check valves, a pressure
connection to the top of said trap casing 80
provided with an inwardly seating valve,
an outwardly seating relief valve at the top
of said casing, a pivoted lever, said pressure
connection and relief valves having a direct
pivotal connection to said lever whereby 85
they are alternately opened and closed as
the lever is actuated, a float rod having a
direct pivotal connection to said lever and
provided with spaced tappets, a closed float
slidably mounted on said rod to coat with 90
said tappets whereby the relief valve is
closed and the pressure valve opened when
the float is lifted and the pressure valve
is closed and the relief valve opened when
the float falls, said float being of such pro- 95
portion that the buoyancy thereof when sub-
merged beyond its floating point sufficient to
overcome the resistance of the pressure on
the pressure valve will actuate the lever with
a snap action to open said valve without 100
the aid of a spring, and of such weight that
when the resistance of the pressure on the
relief valve is overcome by the falling of
the float the lever will be actuated with a
snap action to open said relief valve without 105
the aid of a spring.

3. In an apparatus of the class described, the combination of a return pipe provided with a pair of check valves, a trap casing connected at its lower end to said pipe between said check valves, an inwardly seating pressure valve at the top of said casing, an outwardly seating relief valve at the top of said casing, a pivoted lever having direct pivotal connections to said valves whereby they are alternately opened and closed, a float rod having a pivotal connection to said lever, a float slidably mounted on said float rod, said rod being provided with tappets with which said float coats, said float being of such proportion that the buoyancy thereof when submerged beyond its floating point sufficient to overcome the resistance of the pressure on the pressure valve will actuate the lever with a snap action to open said valve without the aid of a spring, and of such weight that when the resistance of the pressure on the relief valve is overcome by the falling of the float the lever will be actuated with a snap action to open said 130

relief valve without the aid of a spring, and a vent pipe for said float opening at the top thereof and opening into the float at a point adjacent the bottom thereof whereby 5 the interior of the float is subject to the variations in pressure within the casing and water is exhausted from the float.

4. In an apparatus of the class described, the combination of a return pipe provided 10 with a pair of check valves, a trap casing connected at its lower end to said pipe between said check valves, an inwardly seating pressure valve at the top of said casing, an outwardly seating relief valve at the top 15 of said casing, a pivoted lever having direct pivotal connections to said valves whereby they are alternately opened and closed, a float rod having a pivotal connection to said

lever, a float slidably mounted on said float rod, said rod being provided with tappets 20 with which said float coacts, said float being of such proportion that the buoyancy thereof when submerged beyond its floating point sufficient to overcome the resistance of the pressure on the pressure valve will actuate 25 the lever with a snap action to open said valve without the aid of a spring, and of such weight that when the resistance of the pressure on the relief valve is overcome by the falling of the float the lever will be actuated with a snap action to open said relief valve without the aid of a spring. 30

In witness whereof I have hereunto set my hand.

LEONARD D. GOFF.
